(57) **CLAIM**

The ornamental design for a flying disc toy, as shown and described.

DESCRIPTION

FIG. 1 is a top perspective view of the subject flying disc toy illustrating my new design;

FIG. 2 is a bottom perspective view of the flying disc toy;

FIG. 3 is a side view of the flying disc toy. The opposite side view, front view and rear view is the same as this illustration shown in FIG. 3 of the flying disc toy;

FIG. 4 is a top view of the flying disc toy; and,

FIG. 5 is a bottom view of the flying disc toy.
